Primary Examiner — Janice Hallmark*Assistant Examiner* — Rodolfo Castro, Jr.(74) *Attorney, Agent, or Firm* — Barnes & Thornburg LLP(57) **CLAIM**

We claim the ornamental design for a desk stand, as shown and described.

DESCRIPTION

FIG. 1 is a front perspective view of a desk stand in accordance with our new design;

FIG. 2 is a front elevation view of the desk stand of FIG. 1; FIG. 3 is a rear elevation view of the desk stand of FIG. 1; FIG. 4 is a right side elevation view of the desk stand of FIG. 1, the left side elevation view being a mirror image thereof; FIG. 5 is a top plan view of the desk stand of FIG. 1; and, FIG. 6 is a bottom plan view of the desk stand of FIG. 1. The broken lines depict portions of the desk stand that form no part of the claimed design.

1 Claim, 6 Drawing Sheets# US D1,028,964 S
